UNITED STATES PATENT OFFICE.

ARTHUR C. ROTHENBERG, OF ST. LOUIS COUNTY, MISSOURI, ASSIGNOR TO OTIS ELEVATOR COMPANY, OF JERSEY CITY, NEW JERSEY, A CORPORATION OF NEW JERSEY.

MOVABLE PLATFORM FOR PUSH-BUTTON ELEVATORS.

1,382,243.

Specification of Letters Patent. Patented June 21, 1921.

Application filed May 27, 1920. Serial No. 384,519.

To all whom it may concern:

Be it known that I, ARTHUR C. ROTHENBERG, a citizen of the United States of America, residing in St. Louis county in the county 5 of St. Louis and State of Missouri, have invented a new and useful Improvement in Movable Platforms for Push-Button Elevators, of which the following is a specification.

10 My invention relates to improvements in push-button-operated electric elevators; and the objects of my invention are: first, to enable a person in a building installed with a push-button-operated elevator, to obtain 15 control of the car at any floor, when there is nobody in the car, all the doors on the elevator shaft closed, and the gate in the car left open by the last passenger leaving the car; second, to prevent the car from being 20 put in motion by a person in the car, without all the doors on the elevator shaft and the gate in the car closed; third, to transmit the motion of any particular point of a movable platform over the entire platform; fourth, to 25 eliminate a feeling of insecurity to a passenger when stepping on a movable platform.

I attain these objects by the mechanism illustrated in the accompanying drawings, in which Figure 1 is a diagrammatical illustration 30 of a single push-button elevator and Figs. 2 and 3 are detailed views of a movable platform in the car.

Similar letters and numerals refer to similar parts throughout the several drawings.

35 A push-button-operated elevator without a regular operator on duty in the car, like in apartment houses for instance, has hitherto caused considerable inconvenience, when the last passenger left the car and forgot to close 40 the gate in the car. The doors on the elevator shaft in those instances are generally supplied with self closing devices, and as the electric controlling apparatus was hitherto inoperative when the gate in the car and the 45 contact operated by that gate were not closed, people desiring to make use of the elevator would first have to locate the car at whatever floor it stopped last and close the gate. This 50 inconvenience I eliminate by leaving out a section of the regular platform in the car, immediately in front of the door and installing a movable section instead.

Referring to Figs. 2 and 3, 10 designates the regular car platform, 11 the movable sec-

tion of the platform, made up of sheet steel 55 reinforced with the angle irons 12, to fit the opening left in the platform 10. At each corner of the movable platform, 11, a pin, 13, is fastened by means of the casting, 14, which is bolted to the platform, 11. The castings 14 60 and pins 13 are threaded for adjustment. The pins 13 pass through the brackets 15 which act as guides for the pins 13 and are bolted to the regular platform 10.

Brackets 15 also support shafts 16 by 65 means of the trunnion screws 38. Each end of the shafts 16 is tapered, hardened and ground to fit the bearing part of the trunnion screws 38, so as to reduce the friction. The levers 17 are pinned on shafts 16. When a 70 person steps on the movable platform 11 motion is transmitted to the levers 17 through pins 13 and the sockets 18 on the levers 17. This travel is limited to about $\frac{1}{2}$ " 75 by the space between the leather washers 19 and finished surface on casting 14. Between the pins 13 and sockets 18 on levers 17, a ball bearing 20 is used to reduce friction.

The levers 17 are connected in the center 80 with the links 21 so that movement at any point of the platform 11 is transmitted over the entire platform 11. An electric contact 22 is mounted on a stationary bracket 23 and is operated by one pair of levers 17 and in connection with the other pair of levers 17 is 85 placed a weight lever 24, which is pivoted on the bracket 25, the latter being fastened on the stationary angle iron 26. One end of this weight lever 24 is connected to the said pair 90 of levers 17 by means of a link 27 and on the other end is the weight 28 which serves to raise the movable platform 11 when a passenger in the car steps off same. An air dash pot 29 is connected with the weighted lever 24 to take care of momentum of weight 28 95 and lever 24 and so prevent same from striking the under side of the movable platform, 11.

The movable platform 11 is so placed, that a person entering the car will step upon it 100 and will have to stand there while pushing the button for operating the elevator. Hitherto, a passenger, when stepping upon a movable platform, had a feeling of insecurity, caused by the wobbling of the movable platform or too much or too quick descending of the movable platform. I eliminate that feeling of insecurity, as can be seen 105

from Fig. 3, first, by having the pins 13 fit snugly in the top and bottom of the guides 15, the latter being securely fastened to the stationary platform 10, and second, by having the motion of the platform retarded by the dash-pot 29. With these arrangements, it is obvious that practically no wobbling of the platform is possible and as the vertical motion of the platform is limited to about $\frac{1}{8}$ " 5 and at the end of the motion the platform rests upon the leather washers 19, which act at the same time as shock absorbers, the movement of the platform is practically not felt by any person stepping upon the movable 10 platform.

Referring now to Fig. 1, which represents a diagrammatical illustration of a complete push-button elevator, B¹, B² and B³ are the push-buttons in the car, corresponding to the 20 number of the floors; HB¹, HB² and HB³ are the buttons located in the hall on each individual floor; SB is the stop button in the car; C is the elevator car; B the hoisting cables; D the counterweight; 30 is the driving sheave; 31 is the brake magnet; M is the hoisting motor; G is the governor; F is the floor controller, which is connected to some slow moving part of the hoisting apparatus; E¹, E² and E³ are the doors in the elevator 30 shaft which when shut, close the contacts, D¹, D² and D³, respectively. The doors in the elevator shafts are hanging on rails, which are slightly tilted at one end, so as to cause the doors to be self closing. The doors 35 are locked when the car is in motion by the locks L¹, L² and L³. These locks close by gravity and are released, when the car is approaching the landing, and the operating circuit is interrupted at the floor controller 40 F, and the cam magnet K has released its plunger and caused the cam 32 to drop back to its position, as shown, and engaged the roller of the door lock, thereby unlocking the door.

45 L and LL are the limit switches in the hatchway; H is the main line switch; N and O are the reversing switches for the hoisting motor M; P is the accelerating switch which short circuits gradually the starting resistance V; T is the stopping resistance; R is the car holding magnet; S the non-interference magnet; U¹, U² and U³ are the floor magnets; 33 and 34 are fuses in the operating circuit; and 35 is the gate contact which 50 is closed, when the collapsible gate in the car is shut.

I think it is unnecessary to explain the operation of the controlling apparatus as the latter is a well known system of push-button control. It should, however, be noticed, that the contact 35 on the collapsible gate and the contact 22 under the movable platform are in parallel and that the current for the entire operating circuit, coming from the 55 positive fuse 34, has to pass through the door

contacts E¹, E² and E³, and through either one or both the gate contact 35 or the contact 22 under the movable platform. It is obvious that all the doors should be closed and either the gate contact 35 or the contact 70 under the movable platform 11 closed, before the controlling apparatus can get in operation and start the car in motion.

The action of my invention is as follows: A person entering the car has to step on the 75 movable platform 11, which descends about $\frac{1}{8}$ " and through the levers 17, interrupts the operating circuit through the contact 22 under the movable platform 11. In order to get the car in operation, the passenger must 80 close the collapsible gate, which closes the contact 35 to complete the operating circuit. When leaving the car, the weight 28 returns the movable platform 11 to its normal position and closes the contact 22 under the platform 11, thereby completing the operating 85 circuit and eliminating the necessity of closing the car gate. In view of this operation, a passenger at any landing may call the elevator car even though the collapsible gate 90 in the car is left open, as the doors on the elevator shaft are self closing.

I am aware that prior to my invention, elevator cars have been made with movable platforms. I, therefore, do not claim such 95 a combination broadly, but, what I claim is:

1. The combination of an electric elevator, a movable platform in the car, means to transmit the movement at any point over the entire movable platform, an electric contact opened and closed by said movable platform, said contact being in parallel with the contact on the gate in the car and in series with the common feed wire of the 100 operating circuit.

2. The combination of a push-button-operated electric elevator, a platform in the car, part of said platform being movable and located so that a person has to stand on said movable section of the platform to 110 start the car in operation, means to transmit the movement at any point of the movable section over the entire section of said platform, an electric contact operated by the movable section of said platform, said contact in parallel with the contact on the collapsible gate in the car and in series 115 with the common feed wire of the operating circuit.

3. The combination of an electric elevator, 120 self closing doors on the hatchway, a movable platform in the car, levers under the movable platform to transmit the movement at any point over the entire movable platform, an electric contact opened and closed 125 by said movable platform, means to retard the motion of the movable platform, and means to raise the movable platform to its normal position after the load on said movable platform has been removed, a contact 130

in the car operated by the collapsible gate in the car, said contact in parallel with the contact operated by the movable platform and in series with the common feed wire 5 of the operating circuit.

4. The combination of a push-button-operated electric elevator, self closing doors on the hatchway, contacts on said doors, said contacts in series with each other and in 10 series with the common feed wire of the operating circuit, a movable platform in the car, levers under the car to transmit the movement at any point over the entire platform, a dashpot mechanically connected 15 to said levers to retard the motion of the movable platform, a weight connected mechanically to said levers to raise the said movable platform after the load has been removed from the movable platform, an electric contact operated by the said movable platform and closed when there is no load 20 on movable platform, an electric contact operated by the collapsible gate in the car and closed when said gate is closed, the contact operated by the movable platform in 25 parallel with the contact operated by the collapsible gate and in series with the common feed wire of the operating circuit.

5. The combination of an electric elevator, 30 a movable platform in the car; adjustable pins on each corner of said movable platform and guides for said adjustable pins, said guides fastened to the stationary platform of the car, leather washers between the top 35 of said guides and the movable platform, levers under the movable platform and operated by said pins, said levers connected by a link to transmit the movement at any 40 point of the movable platform over the entire movable platform, a weight to return

said movable platform to its normal position and a dashpot to retard the motion of the movable platform and said weight.

6. In an electric push-button elevator, the combination of a substantially parallel- 45 movement movable platform in the car, means to transmit the movement of the movable platform at any point over the entire movable platform, and an electric contact in the elevator-operating circuit, adapted to 50 be opened and closed by the movement of the movable platform.

7. In an electric push-button elevator, the combination of a movable platform in the car, adapted to be moved up and down relatively to the car, throughout its area to 55 planes substantially parallel to the horizontal plane of the car and an electric contact in the operating circuit of the elevator, adapted to be opened and closed by the 60 movement of the movable platform.

8. In an electric push-button elevator, the combination of a platform in the car, adapted to be moved substantially parallel to itself vertically relatively to the car, levers under 65 the said platform, adapted to transmit its movement at any point over the entire platform, means to raise the said platform when its load is removed, and an electric contact in the operating circuit of the elevator, 70 adapted to be opened and closed by the movement of the said platform.

In testimony whereof I have signed my name to this specification in the presence of two subscribing witnesses.

ARTHUR C. ROTHENBERG.
